UNITED STATES PATENT OFFICE.

WILFRED ROTHERY WOOD, OF LONDON, ENGLAND.

MECHANICALLY-OPERATED GRATE FOR FURNACES.

1,141,226.

Specification of Letters Patent. Patented June 1, 1915.

Application filed November 28, 1914. Serial No. 874,537.

To all whom it may concern:

Be it known that I, WILFRED ROTHERY WOOD, a citizen of the United States of America, and a resident of London, England, have invented certain new and useful 5 Improvements in and Connected with Mechanically-Operated Grates for Furnaces, of which the following is a specification.

This invention relates to that class of 10 furnace grate in which reciprocating movement is imparted to the grate bars for the purpose of breaking up the fuel mass and feeding same forward to the point of discharge.

15 The invention is herein described and illustrated as applied to that form of under-feed or mechanical stokers described in prior specification No. 818010, dated April 17th, 1906, but the present improvements 20 can obviously be applied to other forms of furnaces in which the fuel is fed on at one end of the grate bars and discharged at the other ends some or all of such bars being reciprocated.

25 The accompanying drawing shows partly in elevation and partly in section a furnace grate such as illustrated particularly in Figure 6 of said prior specification, but with the present improvements applied thereto and the same figures of reference are employed 30 in both sets of drawings.

In the drawings accompanying the present application the usual feed hopper 1 delivers the fuel to the fuel magazine or 35 retort 5 along and up to which it is fed in the well known manner on the bottom 17, and passes on to the grate bars 14 where final combustion takes place, the ash and clinker being eventually delivered to the dumping 40 plate or grate 20.

To assist the feed down bars 14 and also 45 to prevent the fuel caking thereon alternate bars 14 are preferably reciprocated and also given a slight rising and falling motion and this may be obtained by rocking bars 13 adapted to engage with notches 15 on the under side of the grate bars the rocking bars being operated by guide pieces or nuts 12 and spiral feathers or projections 22 moved 50 in unison with the fuel feed as described in my prior specification, but according to the present invention the outer end of the movable bars 14 also has a rising and falling movement as it reciprocates on the inclined 55 top 24 of the supporting bar 23 all as more fully hereinafter set forth. The air to sup-

port combustion passes from draft box 18 up to the retort 5 and also down the hollow grate bars 14 to ash pit 19 and up through the dumping plates 20, as indicated by the 60 arrows.

The details of the present invention and points of difference from those described in my prior specification will now be set forth.

In the prior specification it will be noted 65 that the outer end of the moving hollow grate bar 14 is substantially above the level of the dumping grate and reciprocates in a practically horizontal plane on the bar or frame carrying the trunnions of the dump- 70 ing grate 20 and that the flow of air down grate bar 14 is somewhat impeded when its discharge opening is resting upon the solid portions of such bar or dumping grate and also that even if the inner end of grate bar 75 14 be slightly raised during reciprocation by the rocking bar 13 still the outer end of 14 will practically have only a horizontal reciprocating movement and while this is sufficient with certain classes of fuel ash and 80 cinder yet with others better results can be attained if the mass is somewhat raised as it is forced forward and also better results are attained if there is always a free flow 85 for the draft through the grate bars 14 into the ash pit 19 and up through the dumping grates 20 without such draft being restricted by the partial closing of the discharge aperture by the movement of the bars. It will 90 also be noted that the outer rounded end of the bar stands up above the dumping grate so as to be always subject to very considerable heat of the fuel and ash being fed forward and this with certain classes of fuel 95 causes a rather rapid burning away at this point.

According to the present invention the top of the supporting bar 23 is inclined upwardly at 24 as is also the underside of the closed outer end of grate bar 14 the 100 construction being such that as the bar 14 is reciprocated its outer end has a rising and falling movement over the inner end of dumping grate 20 thus breaking up and at 105 the same time feeding forward the ash and clinker, and also the air from the draft box 18 always has a free discharge through the grate bars 14 into the ash pit 19 at points behind the supporting bar 23. Further by 110 tapering off such bar 14 it is possible to bring its outer end almost in line with the top face of the dump plate 20 so that burn-

ing away at this point is substantially retarded, and this end is greatly assisted by making the extreme outer end of bars 14 solid wedge shaped in cross section and 5 placing the draft opening farther back in the lower face of said bars. A further improved feature is adapting the dumping grate 20 so that when in its normal closed position it will be practically in the same 10 plane as the top of bar 14 and preferably at approximately the same inclination: This will enable such dumping grate to receive and deal with a larger quantity of ash and 15 cinder without clogging than when such grate is horizontal.

Various means may be employed to feed the fuel to the furnace and to cause the grate bars of such furnace to reciprocate, and it is not deemed necessary to describe 20 them in detail as other means than those indicated of fuel feeding and for causing the bars of various shapes to reciprocate can be employed, but the construction indicated in the drawings and described in prior 25 United States specification No. 818010 is effective for the purpose.

What I claim is:—

1. In furnace grates of the class having hollow reciprocating grate bars of box like 30 cross section adapted to carry the draft and in combination, means for reciprocating the bars, a substantially wedge shaped outer end to the movable bars, a supporting bar having an upwardly inclined surface forming 35 a support for the lower face of the wedge shaped end of the movable bar so that a rising and falling movement is produced as the bar reciprocates, and a dump plate over the inner edge of which the movable bars can reciprocate.
2. In furnace grates of the class having hollow reciprocating grate bars of box like 40 cross section adapted to carry the draft and in combination, means for reciprocating the bars, a substantially wedge shaped outer end to the movable bars, a supporting bar having an upwardly inclined surface forming 45 a support for the lower face of the wedge

shaped end of the movable bar so that a rising and falling movement is produced as the 50 bar reciprocates, a dump plate over the inner edges of which the movable bars can reciprocate the top surface of said dump plate being placed practically in the same plane as the top surface of the bars and 55 approximately at the same inclination.

3. In furnace grates of the class having hollow reciprocating grate bars of box like cross section adapted to carry the draft and in combination, means for reciprocating the 60 bars, a substantially wedge shaped outer end to the movable bars, a supporting bar having an upwardly inclined surface forming a support for the lower face of the wedge shaped end of the movable bar so that a 65 rising and falling movement is produced as the bar reciprocates, a draft opening from the hollow bar on the furnace side of said supporting bar and a dump plate over the inner edge of which the movable bars 70 can reciprocate.

4. In furnace grates of the class having hollow reciprocating grate bars of box like cross section adapted to carry the draft and in combination, means for reciprocating the 75 bars, a substantially wedge shaped outer end to the movable bars, a supporting bar having an upwardly inclined surface forming a support for the lower face of the wedge shaped end of the movable bar so that a 80 rising and falling movement is produced as the bar reciprocates, a draft opening from the hollow bar on the furnace side of said supporting bar, a dump plate over the inner edge of which the movable bars can 85 reciprocate, the top surface of said dump plate being placed practically in the same plane as the top surface of the bars and approximately at the same inclination.

In testimony whereof I have hereunto set 90 my hand in the presence of two subscribing witnesses.

WILFRED ROTHERY WOOD.
